United States Patent Office.

WILLIAM A. LIGHTHALL, OF NEW YORK, N. Y.

Letters Patent No. 76,929, dated April 21, 1868.

IMPROVEMENT IN CONDENSERS.

The Schedule referred to in these Letters Patent and making part of the same.

TO ALL WHOM IT MAY CONCERN:

Be it known that I, WILLIAM A. LIGHTHALL, of the city, county, and State of New York, have invented certain new and useful Improvements in Surface-Condensers for Steam-Engines; and I do hereby declare that the following is a full and exact description of the same, reference being had to the accompanying drawings, and to the letters of reference marked thereon, in which—

Figure 1 is a vertical cross-section.

Figure 2 is a horizontal cross-section.

Figure 3 is a vertical longitudinal section.

In the ordinary method of constructing surface-condensers for steam-engines, the said condensers being intended and used for condensing the exhausted steam from the engine, and creating a vacuum in the same—the steam is generally exhausted into the condenser by a single opening, directly upon the tubes with which the said condenser is filled—the operation of this exhaust-steam upon the tubes is found, in practice, to cut the material of the tubes away, which not only injures the condenser, but also injures the boilers of the engine, by the material thus cut away being taken away by the feed-pumps to the boilers, and by the action of the differing metals—copper and iron—producing a galvanic action that is proved, in practice, to be very destructive to the boilers, at the same time that it proves destructive to the action of the condenser, by the cutting away of the material of the tubes in the same, as before stated.

There has been an arrangement used to prevent this action on the tubes, by interposing a plate between the exhaust-pipe from the engine and the upper series of tubes in the condenser, but this arrangement has been found, by trial, to be of no practical benefit, the same destructive action ensuing from its use as is named above.

The object and purpose of my invention are to overcome and remedy this defect, and the destructive action above named, by providing, in a surface-condenser, an open space between the sections of tubes contained therein, whether the said space is made horizontally or vertically, so that the exhausted steam shall pass into such open space, (without being brought into contact with the mass of the tubes,) and shall then be distributed amongst and around and by the tubes contained in the condenser to be condensed, to produce the required vacuum in the condenser, and from that to the engine, to which it is connected, and, also, by providing an exhaust-pipe, attached to the condenser by a series of nozzles, (two or more,) in which the steam from the engine is exhausted on its passage to the condenser, by means of which the exhausted steam is so distributed throughout the length of the condenser that the destructive action due to a single exhaust-opening into the condenser is avoided.

A, in the accompanying drawings, is the condenser-case. B is the series of tubes, through which the cooling-water, to produce condensation, passes, and around, amongst, and by which the steam exhausted from the engine to be condensed passes. C is the inlet for the cooling-water, through which the cooling-water passes into the end of the case A, and from thence passes through the lower section of the tubes B, and returns through the upper section of the tubes, to pass outward from the condenser through the outlet D.

As this condenser is mainly intended for vessels using steam-power for propulsion at sea, or in rivers or localities where the water is impure, the supply of cooling-water to pass through the tubes, as above named, can be supplied in such localities and positions by any means now known or used.

As seen by the drawings, a space is left between the lower and upper sections of the tubes B, into which space the exhaust-steam from the engine first passes, before being distributed amongst, around, and by the said tubes to be condensed, and, by this means, the destructive action before named is entirely avoided. This same result ensues whether the vacant space is left between the series of tubes in their height, where the space is made horizontally, or if it is left between the series of tubes in their width, where the space is made vertically.

By thus placing the tubes in the surface-condenser, and by attaching thereto the exhaust-pipe, from the engine, with its series of openings, as shown and described, the destructive action due to the ordinary method of constructing and arranging surface-condensers is entirely avoided.

E is the exhaust-pipe attached to the condenser, with the openings F F E, through which the steam exhausted from the engine enters into the condenser, to effect the purpose set forth.

What I claim as my invention, and desire to secure by Letters Patent, is—

Arranging the exhaust-pipe from the engine, with its series of openings, as shown, in relation to the vacant space between the series of tubes, as and for the purpose herein set forth.

WM. A. LIGHTHALL.
